US00D588596S

(12) **United States Design Patent**
Mazzone et al.

(10) **Patent No.:** **US D588,596 S**
(45) **Date of Patent:** **** Mar. 17, 2009**

(54) **CODED INFORMATION READER**

(75) Inventors: **Claudio Mazzone**, Crespellano (IT);
Stefano Vassura, Rastignano (IT);
Corrado Tasselli, Sala Bolognese (IT);
Monica Alegiani, Silvi (IT); **Massimo Lotti**, Rimini (IT)

(73) Assignee: **Datalogic, S.p.A.**, Lippo Di Calderara Di Reno (Bologna) (IT)

(**) Term: **14 Years**

(21) Appl. No.: **29/305,454**

(22) Filed: **Mar. 20, 2008**

Related U.S. Application Data

(62) Division of application No. 29/248,141, filed on Jul. 31, 2006, now Pat. No. Des. 570,843.

(57) CLAIM

We claim the ornamental design for a coded information reader, as shown and described.

DESCRIPTION

FIG. 1 is a front perspective view of a coded information reader according to the present invention;

FIG. 2 is a rear perspective view thereof;

FIG. 3 is a front view thereof;

FIG. 4 is a right side view thereof;

FIG. 5 is a left side view thereof;

FIG. 6 is a rear view thereof;

FIG. 7 is a top view thereof; and,

FIG. 8 is a bottom view thereof.

The portions shown in broken line are not claimed.
